UNITED STATES PATENT OFFICE.

ERNEST L. RANSOME, OF NEW YORK, N. Y., ASSIGNOR TO RANSOME INTERNATIONAL CONDUIT CO., OF NEW YORK, N. Y., A CORPORATION OF MAINE.

APPARATUS FOR LAVING CONCRETE SIDEWALKS, CURBS, &c.

940,061.

Specification of Letters Patent. Patented Nov. 16, 1909.

Application filed December 17, 1907. Serial No. 406,832.

To all whom it may concern:

Be it known that I, ERNEST L. RANSOME, of the city of New York, county of Richmond, and State of New York, have invented certain new and useful Improvements in Apparatus for Laying Concrete Sidewalks, Curbs, &c., of which the following is a full, clear, and exact specification, such as will enable others skilled in the art 10 to which it appertains to make and use the same.

My present invention relates to the construction of concrete sidewalks, curbs, gutters, pavements and other similar structures 15 by means of a traveling mold which advances progressively with the formation of the work. In accomplishing this end, I construct the mold with the cross sectional form of the work to be produced and arrange it 20 so that the plastic concrete may be charged or packed in the mold as the same is moved forward progressively with the formation of the work. The mold in moving over the concrete, shapes and smoothes the same and 25 leaves the concrete in the finished state and form which it is desired to give the side walk, curb or other work constructed.

My invention involves various other features of importance, all of which will be 30 fully set forth hereinafter and particularly pointed out in the claims.

Reference is had to the accompanying drawings, which illustrate, as examples, various forms of the invention, and in which, 35 Figure 1 is a plan view of the invention adapted as a side walk mold; Fig. 2 is an enlarged section of the main part of the mold on the line 2—2 of Fig. 1; Fig. 3 is a cross section on the line 3—3 of Fig. 1; Fig. 40 4 is a plan view of a form of the invention adapted for the simultaneous construction of a transversely continuous sidewalk, curb or gutter; Fig. 5 is a longitudinal section thereof on the line 5—5 of Fig. 4; Fig. 6 is 45 a cross section on the line 6—6 of Fig. 4; Fig. 7 is a plan view of the apparatus adapted as a curb and gutter mold, showing in connection therewith, certain devices for facilitating the movement of the apparatus 50 and for dividing the work transversely; Fig. 8 is a side elevation of the curb and gutter mold; Fig. 9 is a longitudinal section thereof on the line 9—9 of Fig. 7; Fig. 10 is a longitudinal section of the curb and 55 gutter mold on the line 10—10 of Fig. 7;

Fig. 11 is a rear elevation of the form of the invention shown in Figs. 7—10; Fig. 12 is a cross section on the line 12—12 of Fig. 8; Fig. 13 is a plan view of a modification in the curb and gutter mold; Fig. 14 is a cross section on the line 14—14 of Fig. 13; and Fig. 15 is a detail section on the line 15—15 of Fig. 13.

Referring first to Figs. 1, 2, and 3, which illustrate a form of the invention adapted to laying concrete sidewalks, the molding apparatus proper comprises runners 20 from which vertical walls 21 rise. These vertical walls are connected at the rear part of the apparatus by a horizontal molding 60 wall 22 which is adapted to run over the top of the work and finish off the same as will hereinafter fully appear. The runners 20 support the apparatus in the trench or on the level ground according to the 65 manner in which the side walk is laid; and the front of the apparatus is provided with a means 23, which may be of any desired sort, by which the apparatus is drawn along as the construction of the pipe 70 progresses. The front ends of the runners 20, as shown best in Fig. 1, are tapered outward, as indicated at 20^a for the purpose of enabling the apparatus to be guided in its movement. This is done by packing in earth 75 at or ahead of the tapered portions which, as the apparatus is drawn along, wedge against the earth, thus pushing the apparatus to one side or the other according to 80 the side at which the earth is packed. 90

As indicated best in Figs. 1 and 2, the apparatus is provided at its front end with a transversely disposed hopper 24 open at the bottom and adapted to receive cinders or other material for forming a bed or foundation on which the side walk is laid. Rearward of the hopper 24 is an open space 25 which is provided to receive the concrete constituting the body of the side walk and to allow the same to be laid or packed in place. Rearward of the opening 25 is a cut-off plate 26 which is flanged at its ends and the flanges formed with slots 27 receiving bolts 28 which are adjustable to regulate the height of the cut-off plate and consequently 100 the thickness of the layer of concrete, the cut-off plate smoothing off and limiting the height at which the concrete is packed. The apparatus moving ahead in the direction of 105 the arrow shown in Fig. 2, tends, by the 110

- friction of the concrete on the plate 26, and owing to the direction of inclination of the slots 27, to draw the plate 26 downward and rearward so that should the bolts 28 become loosened, the tendency will be to compress the plate against the concrete rather than allow it to rise, which latter would interfere with the proper operation of the apparatus.
- 10 Rearward of the cut-off plate 26 is an opening 29 which enables the concrete to be observed after having been leveled off by the plate 26; and rearward of this opening is a hopper or box 30 adapted to contain the top finish of a higher grade cement which is spread over the rougher concrete. This hopper 30 is open at the bottom and its rear wall is so disposed that as the apparatus is drawn over the ground, a comparatively thin layer of the top finish is spread out over the rougher concrete in the manner indicated in Fig. 2. The horizontal wall 22 extends from the hopper 30 rearward and has a slight "drag" or downward inclination toward the rear end of the apparatus. This wall, moving with the apparatus, slides over the top of the work smoothing or troweling it off, and leaving the side walk with a smooth finished surface similar to that produced by hand troweling and finishing.
- 15 At the rear portion of the apparatus is arranged a hopper 31 and this is open at the bottom and adapted to contain a dry cement mixture which is spread over the wet top finish in a thin, sprinkled or powdered course. This thin dry mixture is indicated by the broken lines appearing above the top finish at the right hand end of Fig. 2 and its purpose is to give the work a hard surface capable of resisting the impact thereon incident its use as a side walk. If desired, a trailer indicated at 32 in Fig. 1 may be drawn after the apparatus, through links or cables 33. This trailer runs over the finished side walk and presses into the same the dry cement mixture from the hopper 31, having the same effect as hand troweling or rolling which is usually resorted to in hand laid side walks after the dry cement mixture
- 20 is sprinkled on the wet top finish. If desired, a plurality of these trailers may be drawn after the apparatus. The drawing illustrates one example in the interest of brevity. Transverse score lines to prevent cracking and improve the appearance of the work, may be formed by a hand implement in any desired manner and longitudinal scores for the same purpose may be formed by a blade or marker 22^a on the underside of the troweling wall 22 (see Figs. 1 and 2) and on corresponding parts of modifications of this structure. This blade moves with the mold and scores the surface of the side walk as indicated at 22^b in Fig. 1.
- 25 In the operation of the apparatus, the

earth bed or foundation is suitably prepared either by making a slight trench or by leveling off the earth should it be desired to lay the side walk on a level or plane surface. The apparatus is then placed in position and the hopper 24 filled and kept filled with cinders, or such other material as may be employed in lieu thereof, to furnish the bed or foundation on which the side walk is laid. The apparatus is then advanced, causing the ash to be spread out in a layer, the thickness of which is determined by the position of the lower edge of the rear wall of the hopper 24. As soon as the apparatus has advanced sufficiently to spread out this layer of cinders approximately to the point of the cut-off plate 26, the concrete is charged into and packed in the opening 25 from the cut-off plate 25 forward to the hopper 24. The continuing advance of the apparatus causes the plate 26 to slide over the top of the concrete leveling it off and smoothing it down to the predetermined height for the reception of the top finish. The concrete is constantly packed in behind the hopper 24 as the apparatus advances; and as the hopper 30, the same having been filled with the top finish of a higher grade of cement, passes over the concrete, this top finish in plastic form is spread out in a thin layer over the concrete. The thickness of this layer is determined by the elevation of the cut-off plate 26, while the thickness of the pavement is controlled by the elevation of the lower extremity of the rear wall of the hopper 30 above the surface of the concrete. The continued advance of the apparatus brings the hopper 31 over the work and this serves to spread out on the surface of the work a thin layer or sprinkling of high grade cement mixture, which forms a hard surface on the side walk. Finally the trailer or trailers 32 follow the apparatus and press the dry cement mixture into the still plastic top finish, thus finishing the work. During this operation, the apparatus is advanced continuously and progressively with the formation of the side walk at a rate of speed dependent upon the supply and manipulation of the materials. The hopper 24 should be supplied with cinders or other material employed in lieu thereof and the concrete should be packed in through the opening 25 in accordance with the advance of the apparatus. The plate 26 may be adjusted at will to regulate the height of the concrete and the condition of the concrete may be observed freely through the opening 29 immediately before the application thereto of the top finish. The whole apparatus is supported by the runners 20 which bear on and are sustained by the earth. The apparatus should have sufficient weight to hold it in position and this weight may be increased at will by loading

the wall 22 or other convenient part of the device. In this connection the drag of the wall 22 is of great importance since it serves not only to compress and pack the concrete, but also to level off and smooth the same in precisely the same manner that it has heretofore been the custom to manually finish the concrete with the use of trowels, floats and like tools. While the troweling wall 22 is preferably smooth and continuous as shown, it may be modified in various ways without departing from the spirit of my invention, thus it may be made undulatory or composed of one or a series of 15 rollers.

The precise form and nature of the work constructed by my invention may be widely varied, particularly it is pointed out that the apparatus may be so shaped in cross 20 section and so modified otherwise as to lay curbs and gutters integral with the side walk or to lay the curb and gutter or curb or gutter independently of the side walk, which latter may be laid or not by a separate means. Fig. 4, in this connection, 25 illustrates a form of the invention adapted to laying the side walk, curb and gutter in an integral monolithic course and by a single operation, in which (see Fig. 6) *a* 30 indicates the side walk, *b* the curb, and *c* the gutter. The apparatus is constructed so as to shape the work as shown in Fig. 6, and in attaining this end its top or troweling wall has a section 34 adapted to run over 35 the top surface of the side walk and second horizontal section 35 adapted to run over the top surface of the gutter. These sections 34 and 35 both are substantially horizontal; they are at different elevations and 40 preferably of different widths so that the side walk will be wider than the gutter. Said sections 34 and 35 of the troweling wall are connected by a vertical section 36 which runs along and trowels off the curb or 45 the vertical portion *b*, connecting the side walk and gutter.

The apparatus shown in Figs. 4, 5, and 6 is provided with a hopper 37 to receive and distribute the top finish and an opening 38 50 through which the concrete is packed into place. Rearward of this opening are two cut-off plates 39 and 40 which are at different elevations respectively corresponding to the elevation of the sidewalk *a*, and the gutter *c*. It will be observed that the concrete 55 is laid for the sidewalk at a higher elevation than for the gutter and to sustain the concrete while it is being tamped at this higher elevation, the division wall 41 is provided. This wall extends between and separates the cut-off plates 39 and 40 and projects from the hopper 37 forward to the transverse brace 42 at the front of the apparatus. The said division wall 41 runs along 60 the outer surface of the curb *b* molding the

same prior to the engagement therewith of the wall section 36. The cut off plates 39 and 40 are separated from the hopper 37 by openings which serve as observation openings as before described. The transverse 70 brace 42 carries shoes 44 and 45 which are respectively at the elevations of the sidewalk and gutter and bear on the earth as the apparatus is drawn over it. The apparatus is also provided with runners 46 similar to 75 the runners 20 excepting that they are at different elevations;—one at the elevation of the sidewalk and the other at the elevation of the street line on which the gutter *c* is laid.

In preparing the earth to receive the monolithic sidewalk, curb and gutter, it is shaped as indicated in the cross section Fig. 6 where a vertical earth wall 47 separates the elevations of the sidewalk and gutter. For 80 the purpose of protecting this earth wall during the movement of the apparatus over it and while the concrete is being packed against it I provide a vertical supporting plate 48. This plate extends longitudinally 85 of the apparatus projecting suitably ahead of it and rearward of the brace 42 into the open space 38. The position of the supporting plate is such that it will run on the said earth wall 47 and sustain it until the concrete is packed against such wall so that the support of the plate 48 is no longer necessary. This plate extends under the shoe 44 and is attached to the brace 42 by means, for 90 example, of an angle member or knee 49, and 95 at its front end by a diagonal brace 50 attached to the plate 48 and to the cross brace 42.

The operation of the form of the modification of the invention shown in Figs. 4, 5, 105 and 6 will be understood from the previous description. The apparatus is drawn over the earth as the formation of the work progresses. The cinder hopper and the dry cement mixture hopper have not been shown 110 in these figures, but may or may not be employed with this type of the invention as desired. The use of these auxiliaries depends largely upon the nature of the work in hand and illustration thereof in connection with 115 all forms of the invention has been omitted in the interest of simplicity.

Figs. 7 to 12 illustrate an embodiment of the invention designed for forming the curb and gutter alone. Here the apparatus 120 (see Figs. 7 to 12) has runners 51 from which side walls 52 and 53 rise, the walls 52 rising above the walls 53 to a height corresponding to the height of the curb and the walls 53 rising to a height corresponding 125 only to the height of the gutter. These vertical walls are connected by a top molding or troweling wall having substantially horizontal sections 54 and 55 respectively at the elevations of the curb and gutter and connected 130

by a vertical wall 56 which is designed to run along the outer surface of the curb. These walls are clearly illustrated in Figs. 7 to 11. The apparatus is provided with a top finish hopper 57, cut-off plates 58 and 59, charging opening 60, and cross connected members or brace 61 at the front end, all of which are substantially the same as the similar parts before described. The apparatus shown in Figs. 7 to 12 also has a division wall 62 adapted to facilitate the tamping of the concrete at different elevations to form respectively the curb and gutter; and for a reason which will hereinafter appear, the front end of this division wall is held by a bridge 63 of substantially inverted U-shaped (see the full and dotted lines in Figs. 11 and 12). This U-shaped bridge has its vertical members fastened to the sides of the apparatus and its horizontal member arching over between the same. The bridge, therefore, serves not only to sustain the division wall, but also to brace and support the side portions of the apparatus.

I have found that in some forms of construction, the friction occasioned by the engagement of the vertical walls 52 and 53 or one of them with the concrete renders the advancement of the apparatus difficult and in some cases disturbs the concrete. To overcome this, I place against the inner sides of the side walls 52 and 53 loose plates 64 and 64^a. These are placed in position ahead of the apparatus and the concrete is packed in against their inner sides with the result that the apparatus slides freely against the outer sides of the metal plates which lie stationary against the concrete. After the apparatus passes over a particular pair of plates and new plates are inserted ahead of them, the plates behind the apparatus may be removed and the earth at the sides of the trench allowed to fall in against the concrete sustaining it until it sets and hardens. In this way, the concrete is molded smooth at the vertical sides without involving the necessity of dragging the apparatus along the surface of the concrete at these points. On the top surface, however, the walls 54, 55, and 56 run and exert on the top finish from the hopper 57 the same troweling or smoothing effect hereinbefore described. In this manner, the surfaces of the curb and gutter which are exposed are troweled or finished off, while the surfaces opposite the walls 52 and 53, which are covered by the earth after the curb and gutter is built, need not be so finely finished. I take advantage of this fact to insert the plates 64 and 64^a. As shown in Fig. 7, these plates lie in openings 65 and 66 in the front member 61 so that the apparatus may be freely moved without moving the plates 64 and 64^a. As is also shown in Fig. 7, said plates may be connected, if desired, by U-bolts or other forms

of fastenings 67 which bolts hold the plates in the proper relative position, but which may be readily released to permit removal of the loose plates as desired. I desire it understood that the use of these loose side plates is in no sense limited to the particular form of mold shown in Figs. 7 to 12, but that such plates may be employed with various other forms of the invention.

In the construction of the curb and gutter according to the method shown in Figs. 7 to 12 as well as in the construction of other similar work by modifications of the form of invention there shown, it is frequently desirable to cut or divide the work transversely so that it will not crack irregularly from exposure to the weather. I provide for this contingency by the devices shown in Fig. 7 consisting of groups of transverse plates designated 68 and 69, of which the plates 68 are the central plates and the plates 69 are the side plates. These plates are arranged in groups of three at desired intervals and extend transversely across between the loose plates 64 and 64^a. The ends of the plates are removably held in vertical guides 70 attached to the inner sides of the loose plates 64 and 64^a. In the use of these plates, they are inserted in their guides 70 approximately behind the connecting member 61, and the concrete is packed in between the loose plates 64 and 64^a and the transverse plates. After the apparatus passes over one of the groups of transverse plates and the concrete has hardened sufficiently to permit of it, the transverse plates are removed. This is done by first removing the central plates 68 which slide out readily, metal against metal. After the middle plates 68 are removed, the side plates 69 may be loosened from the concrete and easily withdrawn. The loose side plates 64 and 64^a are also dislodged from the work after the concrete has hardened as explained above, and thereupon the earth falls in against the concrete. By thus arranging the loose transverse plates, the work is divided transversely at regular intervals and cracking is thus avoided. If desired, the curb or other work may be covered with a thin layer of high grade cement which will bridge the transverse division line, and the surface of this thin layer may be indented or cut after the usual manner so as to prevent a jagged or irregular crack. This, however, is not essential.

Figs. 13, 14, and 15 illustrate a form of the invention in which the mold is adjustable to change the form of the gutter. Frequently, it is desirable to form the gutter at different heights and to enable this to be done I make the mold adjustable as shown in the views referred to. From the cross section Fig. 14, it will be observed that the particular type of mold there shown is

adapted to form a gutter much wider than the curb, to which extent the form of the mold differs from that shown in Figs. 11 and 12. To effect the necessary adjustment, I 5 construct the troweling part 71 of the top of the mold, which part forms the upper surface of the gutter so that it may be flexed vertically, thus raising or lowering the level of the gutter. Preferably, the part 71 is 10 flexible, but if desired, a hinge may be applied at the point 72. For so flexing or adjusting the member 71, I provide two or more overhanging beams 73 which are attached to the relatively stationary part of 15 the mold and have bolts 74 adjustably connecting them with the flexible part 71. By manipulating these bolts, said part 71 may be raised or lowered bringing about a corresponding change in the height of the 20 gutter.

The mold shown in Figs. 13 to 15 has at its relatively stationary side a runner 75 and at its opposite side a runner 76. This runner 76 extends loosely past the top finish 25 hopper 77 and has an upwardly extending side wall or flange 78 which slides against the hopper and is adjustably connected therewith by means of a bolt and nut 79. The cut-off plate 80 as well as the front connecting member 81 are rigidly joined to the runner 76 and are connected to the relatively stationary part of the apparatus by means of hinges 82. It will thus be seen that when the part 71 is vertically adjusted, 30 it carries with it the runner 76 and the elements 78, 80 and 81, the top finish hopper 77 and the parts at the left hand side of the apparatus which forms the curb being relatively stationary. Preferably, the side of 35 the mold forming the inner side of the curb is composed of slats 83 shown best in Fig. 14 and with these slats a loose plate 84 is employed as before explained.

Having thus described my invention, what 40 I claim as new and desire to secure by Letters Patent of the United States is:

1. An apparatus for forming concrete work with substantially plane horizontal surfaces comprising a traveling mold having 45 a top molding wall adapted to form such surfaces and side walls extending down from the side portions of the top molding wall and connected to move with the same along the side walls of the work, the bottom 50 of the mold being open.

2. An apparatus for forming concrete work with substantially plane horizontal surfaces comprising a traveling mold having a top molding wall adapted to form such 55 surfaces and inclined downward toward the rear to exert on the work a troweling and compression action and side walls extending down from the side portions of the top molding wall and connected to move with the

same along the side walls of the work, the 60 bottom of the mold being open.

3. An apparatus for molding concrete work, comprising a traveling mold having two horizontally disposed molding surfaces at different elevations, a vertically disposed 65 molding surface connecting them, and side walls extending downward from the outer edges of both of the horizontal walls, the side walls attached to and traveling with the horizontal walls whereby to form a curb 70 and gutter by a single operation.

4. An apparatus for molding concrete work, comprising a traveling mold having a member with a substantially flat horizontally disposed molding surface and vertically disposed walls or molding surfaces attached to and sustaining said horizontal member, the vertical walls moving with the apparatus as a part thereof and having runners 80 at their lower edges which bear on the earth to sustain the apparatus.

5. An apparatus for molding concrete work, comprising a traveling mold having a member with a substantially flat horizontally disposed molding surface and vertically disposed walls attached to the sides of such member and traveling therewith as a part of the apparatus, the bottom of the 90 mold being open.

6. An apparatus for forming concrete 95 work, comprising a traveling mold, the top molding surface whereof is inclined downward toward the rear end of the apparatus and the vertical walls of which are attached to the mold and move therewith as a part 100 thereof, such vertical walls having runners at their lower edges bearing on the earth to sustain the apparatus, whereby as the apparatus is drawn over the work, the said inclined surface exerts a compression and 105 troweling effect.

7. An apparatus for molding concrete work, comprising runners attached to and moving with the apparatus as a part thereof, the runners adapted to engage the earth 110 and sustain the apparatus and a top wall at the rear of the apparatus behind a feed opening, whereby the concrete may be packed into the feed opening and as the apparatus advances the top wall will pass 115 over the concrete shaping the same.

8. An apparatus for molding concrete work, comprising runners attached to and moving with the apparatus as a part thereof, the runners adapted to engage the earth 120 and sustain the apparatus and a top wall at the rear of the apparatus behind a feed opening, whereby the concrete may be packed into the feed opening and as the apparatus advances, the top wall will pass 125 over the concrete shaping the same, said top wall being inclined downward toward the rear for the purpose specified.

9. An apparatus for molding concrete work, comprising a traveling mold having a feed opening in the front portion thereof to receive the body of the work, a hopper rearward of the feed opening to contain the top finish of the work, the section of the mold between said feed opening and the hopper forming a leveling surface for the body of the work and a troweling member rearward of said hopper to smooth the top finish.

10. An apparatus for molding concrete work, having a feed opening in its front portion to receive the body of the work, a hopper rearward of the feed opening to contain and distribute the top finish of the work, the apparatus having a section separating the said feed opening and hopper and serving to level off or finish the top surface of the body of the work and the apparatus being adapted to advance progressively with the formation of the work, whereby the body of the work is laid first and the top finish laid over the same.

11. An apparatus for forming concrete work, comprising a traveling mold adapted to advance progressively with the formation of the work, the mold having means for laying and finishing the body of the work at its front portion and means rearward thereof for laying the top finish, whereby as the mold progresses the body of the work is laid first and the top finish over it.

12. An apparatus for molding concrete work, having a feed opening in its front portion to receive the body of the work, a hopper rearward of the receiving opening to contain the top finish of the work, means between the feed opening and hopper to finish the body of the work said apparatus being adapted to advance progressively with the formation of the work, whereby the body of the work is laid and finished first and the top finish laid over the same, and a molding or troweling member rearward of the hopper.

13. An apparatus for molding concrete work, having a feed opening in its front portion to receive the body of the work, a hopper rearward of the receiving opening to contain the top finish of the work, means between the feed opening and hopper to finish the body of the work said apparatus being adapted to advance progressively with the formation of the work, whereby the body of the work is laid and finished first and the top finish laid over the same, and a molding or troweling member rearward of the hopper, said molding wall inclining downward toward the rear for the purpose specified.

14. An apparatus for molding concrete work, comprising a mold having a charging opening at its front portion a molding wall at the rear of said opening a division plate vertically disposed in said charging opening

to permit laying the concrete at different elevations and a top finish hopper rearward of said molding wall.

15. An apparatus for molding concrete work, comprising a mold having a charging opening at its front portion and a molding wall at the rear, and a division plate vertically disposed in said charging opening to permit laying the concrete at different elevations, the said molding wall having a cross sectional form corresponding to the elevations at which the material is tamped.

16. An apparatus for forming concrete work, comprising a mold adapted to be advanced with the formation of the work, the mold having a charging opening at the front portion adapted to receive the body of the work, a cut-off wall disposed horizontally at the rear of the charging opening, and a hopper at the rear of the cut-off wall to contain and distribute the top finish of the work.

17. An apparatus for forming concrete work, comprising a mold adapted to be advanced with the formation of the work, the mold having a charging opening at the front portion to receive the body of the work, a cut-off wall disposed horizontally at the rear of the charging opening to level off the body of the work, a hopper at the rear of the cut off wall to contain and distribute the top finish of the work, and a molding or troweling member rearward of the hopper.

18. An apparatus for forming concrete work, comprising a traveling mold having a charging opening to receive the body of the work, a hopper forward of the charging opening to receive and distribute a foundation material and means rearward of the charging opening to level off the body of the work.

19. An apparatus for molding concrete work comprising a traveling mold with means for laying and finishing the work progressively with the advance of the mold, an open bottom hopper carried at the rear of the apparatus and adapted to distribute a thin layer of dry powdered material on the work and a trailer having a smooth under surface, the trailer connected to the apparatus and following the same to impress into the work the material distributed by the hopper.

20. An apparatus for forming concrete work, comprising a traveling mold adapted to advance with the formation of the work, the mold having a charging opening at the front portion, a hopper to receive and distribute a foundation material, located forward of the charging opening, a cut-off plate rearward of the charging opening, a hopper rearward of the cut off plate to apply the top finish, a molding or troweling member rearward of the top finish hopper, a hopper rearward of the molding or trowel-

ing member to supply to the surface of the work a coat of dry cementitious material and a trailer moving behind the mold to finish off the work.

5 21. An apparatus for forming concrete work, comprising molding surfaces at different elevations and a guiding plate attached to the apparatus and disposed vertically, said guiding plate being designed to run 10 against a vertical earth wall to sustain the same.

22. An apparatus for forming concrete work, comprising a horizontally disposed molding wall and means for vertically adjusting the same relatively to the stationary 15 parts of the apparatus, the said wall being flexible to permit its said adjustment.

23. An apparatus for forming concrete work, comprising a traveling mold adapted 20 to progress with the formation of the work, the mold having a vertically disposed wall attached to and moving with the same and a relatively stationary member furnishing a wear or friction surface engaging the concrete 25 and past the outer side of which member the said vertically disposed wall moves.

24. An apparatus for forming concrete work, comprising a traveling mold adapted to progress with the formation of the work, 30 and having a top member and depending members at its sides and vertically disposed relatively stationary plates lying between the sides of the concrete and the inner sides of the vertical walls or depending members 35 for the purpose specified.

25. An apparatus for forming concrete work, comprising a traveling mold adapted to progress with the formation of the work and having a top member and depending 40 members at its sides, two vertically disposed relatively stationary plates lying against the inner sides of the vertical walls, and a transverse division means removably placed between the vertical plates.

45 26. An apparatus for forming concrete work, comprising a traveling mold adapted to progress with the formation of the work, and having a top member and depending members at its sides, and two vertically disposed 50 relatively stationary plates lying against the inner sides of the vertical walls, and transverse division means removably placed between the vertical plates, such division means consisting of a group of three 55 independently separate plates.

27. An apparatus for forming concrete work, comprising a traveling mold adapted to progress with the formation of the work,

and a transverse division means adapted to be placed in the path of the mold, whereby 60 the mold may pass over the division means and such means be removed rearward of the mold.

28. An apparatus for forming concrete work, comprising a traveling mold adapted 65 to progress with the formation of the work, and a transverse division means adapted to be placed in the path of the mold, whereby the mold may pass over the division means and such means be removed rearward of the 70 mold, such division means consisting of a gang of independently separable plates.

29. An apparatus for forming concrete work, comprising a traveling mold adapted 75 to progress with the formation of the work, the mold having a part with a horizontally inclined surface adapted to engage an obstruction, whereby to guide the mold by deflecting it horizontally.

30. An apparatus for forming concrete 80 work, comprising a traveling mold adapted to progress with the formation of the work, the mold having earth runners on which it moves and such runners having their front portions inclined horizontally and adapted 85 to engage obstructions, whereby to guide the mold by deflecting it horizontally.

31. An apparatus for forming concrete work comprising a traveling mold having a feed opening for the reception of the body 90 of the work, a top wall rearward of the feed opening to level off the body of the work, the mold having a second feed opening rearward of said top wall to receive the top finish of the work and a second top wall rearward 95 of the second feed opening to smooth and trowel the top finish.

32. An apparatus for forming concrete work comprising a traveling mold having a main portion and a top molding wall 100 adapted to engage the work, said wall inclining downward toward the rear and being rigidly fastened to the main portion of the frame at both of the side edges of the wall, whereby the weight of the apparatus is applied to the work through such top wall and the said wall exerts on the work a positive downward compressive action, serving to pack and finish the same.

In testimony whereof I have signed my 110 name to this specification in the presence of two subscribing witnesses.

ERNEST L. RANSOME.
